DUNCAN KENNER, OF NEW ORLEANS, LOUISIANA; EMMA TUJAGUE KENNER SURVIVING WIDOW OF DUNCAN KENNER, DECEASED

FASTENER TENSIONING AND TYING DEVICE

Application filed April 2, 1925. Serial No. 20,257.

This invention has particular reference to devices for tensioning or constricting a binding means whether the same be wire or strap metal, and the subsequent fastening of the 5 constricting material to form a permanent binding. Such a device finds great usefulness in preparing bundles, bales or other packages for shipping or in the assembly of manufactured articles wherever it is desired to 10 form a quick and permanent tie. Examples of such use are found in the metal strapping for shipment of bales, cartons, boxes, and miscellaneous articles and also in the assembly of broom heads or mop heads to handles.

15 In the application of my invention it is immaterial what the particular form of tying element may be, as the tool is adapted to be used with different varieties and forms of tying material.

20 For purposes of illustration I have shown the tool as adapted to placing a binding upon a shipping crate, although the application to other uses will be clearly understood by those skilled in these arts.

25 In the drawings,

Figure 1 is a plan view of the tool,

Fig. 2 is a side elevation, omitting the hand wheel,

30 Fig. 3 is a longitudinal section taken on the line 3-3 of Fig. 1,

Fig. 4 is a similar section illustrating the tensioning operation,

Fig. 5 shows the binding in completed form,

35 Fig. 6 is a longitudinal section showing the modified form of tie,

Fig. 7 is a perspective view of the link or keeper illustrated in Fig. 6,

Fig. 8 shows the tie completed,

40 Fig. 9 is a longitudinal section showing a further modification during the tensioning operation,

Fig. 10 is a perspective view of the link or keeper and

45 Fig. 11 illustrates a completed tie thus produced.

The improvement herein disclosed provides means whereby a binding wire, strap or analogous member is constricted and fastened around a package, bale, or through loose ma-

terial in order to form a fastening of a permanent nature. By means of the device described hereinafter it is possible to make such a fastening in a variety of ways dependent upon the demands of the occasion and the nature of the materials upon which the work is being done. The device lends itself to the formation of fastenings with or without the utilization of links or keepers. When the latter are used the fastening can be made in several different ways, for example by applying the tensioning upon one end of the binding material and clamping it securely in final form. Again it is possible by the use of this device to use nails or staples for the 55 rapid and secure fastening of the ends as formed. Irrespective of the manner in which the device may be used, it consists essentially of the following parts. The member 12 takes the form of a truncated cone 13 terminating in a mouthpiece having two lips 14, 14, the outer surfaces of which are tapered as shown in Figs. 2 and 3. This body member 12 is hollow and has a longitudinal opening 15 between the lips 14, 14. This opening 60 need not be of greater width than the width of the material which is to pass through it, but it must be broad enough to permit two thicknesses of the material to pass as indicated in Fig. 3. The opposite end of the 65 member 12 carries transverse bearings 16, 17 formed by notches. Substantially in the plane of these bearings there is attached to the member 12 a handle 18 by riveting, screw-threading or the like. While not essential to the mode of operation, it is sometimes very desirable, as will appear later in the specification, to have the member 12 slotted 70 throughout its length along one side as indicated at 19. The bearings 16 and 17 receive 75 a shaft 20. This shaft has means such as the hand wheel 21 for rotating the shaft in the bearings. A ratchet 22 is carried on the shaft 20 closely adjacent to the outer wall of the member 12. Upon the member 12 is pivoted 80 a pawl 23 which serves to engage the ratchet 22 and prevent rotation of the latter while the device is being used to fasten the tie.

85 From Fig. 1 it will be noted that the shaft 20 is diametrically slotted along the longi- 90

95

100

tudinal axis of the member 12 as indicated at 24.

Where the member 12 is slotted throughout its length as indicated at 19, the corresponding slot 24 is carried through the free end of shaft 20 and made to register with slot 19.

The device so constructed may be used in numerous ways, its primary object being to receive one or both ends of the binding wire or strap 25 in the slot 24 of the winding shaft, and to draw up upon the material until proper tension has been exerted. The material may then be nailed, stapled or otherwise fastened to the object which it is desired to hold or in the event that a link or keeper has been threaded upon one or both ends of the material, the tool may be pivoted on its mouth piece 14 to bend the material sharply and thus prevent its loosening during a subsequent fastening step. Several modes of use have been illustrated by way of example and in particular Figs. 2, 3, 4 and 5 illustrate the manner by which both free ends of the binding material may be threaded through the channel 15, slot 19 and slot 24 in which latter the ends are tightly held by a half-turn of the shaft 20. Further rotation of the hand wheel constricts the binding material and applies the desired tension upon its ends. The provision of sloping lips 14, 14 is important in permitting the pivotal movement of the tool at this point in order to clear the way for attaching each part of the binding material by means of a nail 26 and 27 in succession.

During the tensioning operation the pawl 23 prevents reverse movement of the shaft 20, but as soon as the fastening means 26, 27 are applied the pawl is released and the excess ends withdrawn from the tool. They can then be snipped to an appropriate length to permit their being placed in overlapping relation and nailed, as shown at 28 in Fig. 5.

It frequently happens that it is undesirable or impracticable to nail the strap in the above manner and in this case use is made of a link or keeper which may take the form of the flat plate 29 illustrated in Fig. 7. This plate may be given any desired form, it being essential merely that it shall have a central opening. As indicated in Fig. 6, both free ends of the binding strap 25 are passed through the opening in the keeper 29 and then held in the tool in the manner above described. It will in many cases be found that bending the tool in each direction successively after applying tension will put such a crimp in the material as to prevent its inadvertent slipping while the free ends are being withdrawn from the shaft and member 12. The ends are then turned down back upon the keeper in the manner shown in Fig. 8. This forms a reasonably secure fastening without additional precautions.

When, however, it is desirable to make an even more secure fastening, the keeper may take the form 30 shown in Fig. 10. This may be briefly described as a thin metal plate having a central opening and notched at the four corners to produce upstanding lugs 31 spaced sufficiently to permit the passage of the strap 25 between the opposing members of the pairs of lugs 31. In Fig. 9 the mode of operation is illustrated whereby one end of the strap 25 is brought up through the central opening of keeper 30 and bent down between opposing lugs 31. These lugs are then hammered down over the free end of strap 25. The opposite end of strap 25 which has passed around the article to be secured is threaded through the central opening of the keeper and then through the winding shaft as already described. After tension has been applied the tool is pivoted or inclined so that its axis lies in the line defined by the letters A—A in Fig. 9 to prevent the accidental slippage after the tool is removed. After the tool has been removed the end is trimmed and bent down between the lugs 31 which are folded over it for further security.

It is to be noted that the use of the keepers 29 and 30 are of distinct advantage when combined with the device as above described, in that they serve under all conditions to form a fulcrum around which the ends of the material are bent in order to prevent accidental slipping. Again by the use of such a link it is possible to anchor one end of the material to exert the full tension of the device upon the other free end and then to bend the material so that it cannot slip loose before its final fastening.

A fastening made with a keeper in this manner is a novel and effective way to apply either strap or wire binding. Such minor changes in details of construction as may appear to one skilled in the art are of course comprised within the scope of the invention as defined in the following claim.

I claim:

In a strap tensioning device a tapered tubular element having a relatively flat passageway adapted to fit and grip a strap, a slot in the side of said element extending from end to end thereof and forming an open continuation of said flat passageway, a shaft journaled transversely of said tapering element adjacent its larger end and having its axis in the plane of said passageway, a slot in said shaft arranged to register with said flat passageway, means to prevent longitudinal movement of said shaft, and means for applying torque to said shaft.

In testimony whereof, I have hereunto affixed my signature.

DUNCAN KENNER.
